189,037

COMBINED MAGNETIC TAPE RECORDER AND REPRODUCER

Frank T. Walsh, Palo Alto, and Glenn A. Smith, Redwood City, Calif., assignors to Ampex Corporation, Redwood City, Calif., a corporation of California

Filed Oct. 9, 1959, Ser. No. 57,866

Term of patent 14 years

(Cl. D26—14)

Des. 189,037

PAGE 2

FIG. 2

Figure 1 is a front perspective view of a combined magnetic tape recorder and reproducer, the opposite end being substantially a mirror image of the end shown, showing my new design;

Figure 2 is a front perspective view with the cover raised and hinged at the top rear edge;

Figure 3 is a rear elevation view.

Transparent surfaces are indicated by diagonal lines.
We claim:

The ornamental design for a combined magnetic tape recorder and reproducer, substantially as shown and described.
